ARTHUR W. WEEDEN, OF SOMERVILLE, MASSACHUSETTS.

SHIFT MECHANISM FOR TYPE-WRITERS.

1,071,976.

Specification of Letters Patent. Patented Sept. 2, 1913.

Application filed May 20, 1912. Serial No. 698,384.

To all whom it may concern:

Be it known that I, ARTHUR W. WEEDEN, a citizen of the United States, residing at Somerville, in the county of Middlesex, 5 State of Massachusetts, have invented a certain new and useful Improvement in Shift Mechanism for Type-Writers, of which the following is a specification, reference being had therein to the accompanying drawings.

10 My invention relates to mechanism employed in the construction of typewriting machines or the like, for shifting the position of the platen, or of the carriage carrying said platen, relatively to a type bar on 15 which is carried a plurality of characters, so as to locate said platen in a proper printing position with respect to the character which it is desired to bring into printing action.

20 My invention more particularly relates to shifting mechanisms of a kind in which the change in position of the platen is accomplished through the depression of the key end of a key bar producing a swinging 25 movement in a curved path of the free end of said key bar about a fixed pivot, which swinging movement is adapted to effect, through approximate mechanisms engaged by said free end, the desired shift in the 30 position of the platen.

One object of the invention is to construct a mechanism having the capacity of effecting the shift of the platen in a noiseless manner.

35 Another object is to provide a means of supporting and pivoting the key bar so as to permit a displacement, with respect to its normal, of the curved path in which the free end of the key bar moves, when the key 40 is depressed, which displacement is rendered operative, through the connecting mechanisms, to effect a corresponding variation in the position to which the platen is shifted; the construction by which the displacement of the path of movement of the 45 free end is secured further being one which permits such displacement without altering the level at which the key end of the bar is maintained on the key board.

50 My invention therefore resides in a construction for shifting a platen with respect to the type bar, which embodies a means of adjustment permitting a variation in the position to which the platen is shifted with-

out disturbing the normal or initial position of the same, such adjusting means being so constructed that the changes in the position of the same by which the desired variation in the platen shift is secured is without appreciable effect upon the position 60 of the key on the key board; the mechanisms employed further being of such nature as to have the capacity of performing their functions in a quiet and noiseless manner.

65 While my invention is capable of embodiment in many varying forms of shifting mechanisms it lends itself especially to that type of mechanism in which the free end of the key lever engages a cam-groove or 70 cam-surface and in its swinging movement causes the part carrying such cam surface to swing or rotate with respect to its support. My invention also is of especial adaptability in mechanisms by which a 75 double shift of the platen may be provided. I have, therefore, in the following specification more particularly shown and described my invention as embodied in a double shift mechanism for the platens of typewriting 80 machines, or the like, in which the platen derives its shifting movement from the change in position of a cam piece or member effected through the swinging movement of a cam-engaging member carried at the 85 free end of the key bar or key lever, and engaging a cam-surface or cam-groove carried by said cam-piece.

90 Referring to the drawings which accompany this specification and form a part of this application, Figure 1 shows in elevation a platen shifting mechanism of the double-shift type, embodying my invention. Fig. 2 is a plan view of the portions of the mechanism shown in Fig. 1, which particularly 95 relate to my invention, certain parts of said mechanisms being shown in section. Fig. 3 is a side elevation of the bracket on which are mounted the supports on which the key lever is carried. Fig. 4 is an elevation illustrating a modification in the manner of supporting the key lever. Fig. 5 illustrates a further modification in the manner of supporting the key lever, Fig. 6 being a section of the same on the plane $x-x$, of Fig. 105 5. Fig. 7 is a side elevation, partly in section, showing another type of mechanism embodying my invention. Fig. 8 shows a

plan view of the mechanism shown in elevation in Fig. 7, certain portions of the same being shown in section to more clearly illustrate the construction thereof; Fig. 9 5 being an end elevation of the same. Fig. 10 is an elevation showing the construction of a part of the adjusting mechanism. Figs. 11 and 12 are respectively an elevation and a plan view, shown partly in section, of a 10 further modification of my invention, Fig. 13 being an end view of the platen shifting lever and cams actuating the same. Figs. 14 and 15 present a modification of certain 15 portions of the mechanism shown in Figs. 11, 12 and 13.

Referring to the drawings 1 represents a part of the frame or bed of the typewriting machine, on which are carried the frame journals 2, 2, having rotatably mounted 20 therein a shaft 3. On said shaft 3 is carried a lever 4 which is securely fixed thereon as by means of a pin 4^a. The free end of said lever 4 engages the lower end of a link 5 leading to and secured at its upper 25 end, as by a pin 12 to a vertically movable rail 6 on which the carriage 7, carrying the platen 8, travels; said carriage being preferably supported upon said rail 6 by a ball-bearing 9, or other appropriate construction. 30 In the normal position of the platen the same is positioned in proper printing relation with respect to a character 10 carried on a type bar 11, the position of the platen with respect to said character being 35 susceptible to adjustment if desired by means of a slot 12^a, in which the pivot 12, through which the link 5 engages the rail 6 may be adjustably positioned, or in other appropriate manner. The type bar 11 carries 40 besides the character 10, the characters 13 and 14. The mechanism hereinafter described is designed to raise the platen either to the dotted position 8^a, in which it is in proper printing position with respect to the character 13, or to lower the same into the 45 dotted position 8^b, in which the platen is in proper printing position with respect to the character 14. The mechanism preferably adopted to effect the shift in position to the 50 platen either to the position 8^a or 8^b includes, in the embodiment now being described, a cam piece 15 which is rigidly secured to the shaft 3 as by a pin 16. The upper portion of said cam is provided with 55 two cam grooves 17 and 18, in which grooves the rollers 19 and 20, respectively, are designed to travel. Said rollers 19 and 20 are respectively carried at the free ends of the key levers, 21 and 22, which are provided 60 with suitable manipulating keys, 23 and 24, located in the key board of the machine. The rollers 19 and 20 are preferably revolvably mounted, as by pins 19^a and 20^a, secured in forked ends 25 and 26 formed on 65 said keys, said forked ends of said keys be-

ing so formed that either of the same may swing upwardly without interference from the other. For this purpose preferably the forked end 25 carrying the roller 20 and straddling the edge 15^a of the cam is offset, 70 as shown, permitting the upward movement of the same without interference from the forked end 26 of the lever 21, carrying the roller 19 and straddling the forward edge 15^b of said cam; said forked end 26 being 75 in a similar manner free to swing upwardly without interference from the end 25. In Fig. 1 those parts of the forked ends 25 and 26 nearest the observer are broken away, to show more clearly the relations of 80 the lower ends of the grooves 17 and 18, and the rollers 19 and 20 lying therein in their normal position.

The key levers 21 and 22 are independently supported respectively on the brackets 27 and 28, through the combined action of the supporting pins 29 and 30 and of the adjustable pivot rolls 31 and 32. For the sake of clearness the supporting bracket 27 is not shown in Fig. 1, only the pin 29 and the pivot roll 31 being there shown in section. The pin 29 is preferably formed integral with said bracket 27, although the same may be formed and supported thereon with a capacity for change in location or adjustment forward provided if desired, in any approved manner. The bracket 28 is secured to the frame 1, as by cap bolts 28^a and 28^b, engaging said bracket 28 and passing through openings in the said frame, 95 which are preferably slotted to permit an adjustment in the position of the bracket on the frame, if so desired.

The pivot rolls 31 and 32 are carried upon the pins 33 and 34, pin 34 being mounted upon a block 35 adapted to slide within a curved slot 36 formed in the supporting bracket 28, in which slot it may be fixedly secured if desired through a nut 37 engaging a threaded extension 38 of the same, and clamping the block 35 within said slot. Pin 33 is similarly mounted on a block 35^a located in a slot formed in bracket 27, although not shown in Fig. 1. The pivot roll 31 is preferably eccentrically mounted upon the pin 105 33 and is adapted to be fixedly secured in a desired position of rotation upon said pin by means of the nut 39. A similar construction is employed to secure the pivot roll 32 on the pin 34.

The key lever 21 is supported upon the supporting pin 29 and the adjustable pivot roll 31, and the key lever 22 upon the pin 30 and pivot roll 32 in the following manner: Said pin 30 is adapted to slidingly fit 110 within a longitudinal slot 40 provided in the key lever 22. Adjacent said slot and a little to one side of the same, at the right as shown in Fig. 1, there is formed, in a central enlargement 41 of said key lever 22, 115

5 a curved slot 42 of a width adapted to permit the pivot roll 32 to freely slide throughout its entire length. The curvature of said slot 42 corresponds with that of the arc 10 of a circle, described about the center of the roller 20 when the same is at the normal position adjacent the lower end of the cam-groove 18 as shown in Fig. 1. In like manner a curved slot 43 is formed in the key lever 21 having a curvature coincident with that of the arc of a circle described about the center of the roller 19 carried at the end of the key lever 21. The curvature of the slot 36 formed in the supporting bracket 28, 15 and in which the block 35 carrying the pivot roll 32 slides, is also concentric with that of the curved slot 42 of the key lever 22. Similarly the curvature of the slot formed in the bracket 27 is concentric with that of the key lever slot 43. As in the case of lever 20, the pin 29 slidingly fits within a longitudinally elongated slot 44. From this construction it is apparent that the pivot rolls 31 and 32 may be located either near the 25 center of the key lever slots 40 and 44, as shown in Fig. 1, or they may be raised or lowered, within the range of movement permitted, without disturbing the position of the rollers 19 and 20 carried at the ends of 30 said levers, by reason of the fact that said rollers are centrally located with respect to the circular arcs defining the slots in which the pivot rolls 31 and 32 move.

35 From the method of supporting the key levers hereinbefore described it is evident that the pins 29 and 30 will operate to position the keys 23 and 24 always at the desired elevation in the key board. It is also evident that pivot rolls 31 and 32 will serve 40 to control the longitudinal position of the key levers 21 and 22 and of the rollers 19 and 20 carried at the free ends of the same. It is further apparent that the engagement of said longitudinally immovable rollers 19 45 and 20, each against the side of the groove in which it is located, will prevent the cam piece from swinging in either direction, and will hold the cam piece 15 rigidly fixed in its normal position, in which position the 50 platen will be located in its proper printing relation with respect to the character 10. It will also be seen that the depression of the key 23 of the lever 21 will cause the free end of the lever to move upwardly, the 55 swinging of the lever, at the same time causing the slot 43 to move downwardly for a slight amount with reference to the pivot roll 31. Moreover the free end of said lever will swing about the center of which the 60 act location is more or less dependent upon the relative position of the pin 29, and the pivot roller 31, although such location is more especially controlled by the position of the pivot roll 31. The swinging of the lever 65 21 about the pivot roll 31 will in turn cause

a slight longitudinal movement of pin 29 in the slot 44; which movement, although of almost unappreciable amount in the normal position of the roll 31, as shown in Fig. 1, will materially increase as the location of 70 the said pivot roll is changed so that it occupies the dotted positions indicated at 31^b and 31^c and located respectively near the upper and lower ends of the slot 43. The swinging movement of the free end of the 75 key lever 21 is arranged to produce a lowering of the platen into the position 8^b, and that of the end of key lever 22 to produce an elevation of the platen into the position of 8^a in the following manner: The cam groove 17 is of such form that as the roller 19 swings about its support, moving in the curved path *a*, indicated by the dotted line, which path *a* may be assumed to substantially coincide with an arc centered at the 80 normal position of the pivot roll 31, such movement will cause a rotation of the cam piece 15 in an anti-clockwise manner. The said groove is further so designed that at the limit of the swinging movement of the 85 roller 19 a rotation of the cam groove will have been produced sufficient to cause a downward movement of the lever 4 of such extent that the platen will be lowered into position 8^b opposite the character 14. To 90 permit this rotation of the cam piece with respect to the roller 20, which during the swinging movement of the key lever 21 and roller 19 will remain stationary, the lower ends of the grooves 17 and 18 are interconnected, as shown, by the connecting groove 187. Such groove 187 has a length great 95 enough to permit a rotation of the cam piece 15 sufficient to produce the desired lowering of the platen 8, before the position at the 100 lower end of the slot 17, previously vacated by the roller 19 as it is swung upwardly, coincides in position with that of roller 20; the fork 25 at the end of the lever 22, further being of sufficient depth to permit such 105 rotation of the cam piece without bringing the edge 15^a of the cam piece, into interference with the same. In a similar manner the cam groove 18 is so designed that the upward swinging movement of the roller 110 20 through its range of movement will produce a clockwise rotation of the cam piece 15, which will be transmitted through the lever 4 and move the platen 8 into position 8^a, the interconnecting groove 187 at the 115 same time permitting the rotation of the cam piece without interference from the roller 19.

120 The form of the cam grooves necessary to effect the results just described can be 125 readily designed by any competent draftsman, having in mind the desirability of effecting the rotation of the cam to the desired amount by means of the travel of the roller with a gradual movement of the cam sur- 130

face at the start and finish of the path traversed by the roller. A cam piece having cam grooves of the nature shown in Fig. 1 presents one form which such cam grooves 5 may take. Preferably there is a dwell, or portion of the groove which is so designed that the swinging movement of the roller is without effect to move the cam, at the beginning 17^a, 18^a, and at the finish 17^b, 18^b, 10 of each of the cam grooves, such dwell at the beginning of such grooves carrying the lower ends of said grooves somewhat below the rollers traveling therein, so that the lower edge of the connecting groove 187 is somewhat 15 below the rollers 19 and 20. The purpose of such dwell is to permit the rotation of the cam to be completed before the roller impinges against the extreme end of the cam groove. In consequence, stops 45 and 46, 20 secured respectively to frame at 1 and at 1^a, with a capacity for adjustment in height, either by screw 47, or through shims 48, and carrying pads 49 and 50, adapted to absorb the impact of the key lever 21, there- 25 against without noise or shock, may be employed to limit the swinging range of the roller 19 so that its travel in the groove may be stopped without impact of said roller against either upper or lower end of the 30 groove. Thus from the construction just described there results a platen shifting mechanism which effects a change of position of the platen in a quick and easy manner, and without accompanying noise or 35 shock incident to operation.

When it is desired to alter the position into which the platen is raised or lowered by the action of the shifting mechanism, the desired result can be accomplished by a 40 change in the position of the pivot roll about which the proper key lever swings. Thus assuming it to be desired to increase the lowering of the platen, the pivot roller 31 may be raised by loosening the nut 37^a, carried 45 on a threaded extension 38^a of the block 35^a, and moving the block 35^a upwardly in the curved slot formed in the bracket 27, wherein it may be again clamped by retightening said nut 37^a, so as to locate said pivot 50 roller in a new position, for example that indicated at 31^b. This change in position of the pivot roll 31 will not disturb the normal position of the roller 19, as shown in Fig. 1, since by assumption said roller 19 is at 55 the center of the arc upon which said curved slot is defined and through which said pivot roll 31 has been moved. The change will however cause the path in which the roller 19 is carried, as the free end of the lever 60 swings upwardly, to follow substantially along the path *b* inclining at its upper end to the left of the original path *a*. Thus the rotative movement of the cam piece 15 will be greater for a given angular movement of 65 the roller 19 than originally, and the posi-

tion into which the platen will be shifted will consequently be somewhat lowered. Similarly a relocation of the pivot roll 31 in the position 31^c near the lower end of the curved slot 43 will cause the free end of the lever and the roller 19 to follow substantially along the path *c* inclining to the right of the original path *a*, thus lessening the amount of rotative movement of the cam piece and causing the position into which the platen will be shifted to be slightly higher than before. 70 75

Figs. 4, 5 and 6 are designed to illustrate modifications in the manner of supporting the key levers, the supporting pin 30 and slot 40 of the construction shown in Figs. 1 and 2, being replaced, in Fig. 4, by a swinging link 51 pivoted to the lever at 52 and to the bracket 53 at 54, while in Figs. 5 and 6 the lever 55 slides in a yoke 56 which is adapted to swivel with respect to bracket 58 upon a cylindrical projection 57. 80 85

Figs. 7, 8, 9 and 10 illustrate another embodiment of my invention, in which the single cam piece 15, of Figs. 1 and 2, having two cam grooves, is replaced by two independent cam pieces, each carrying a single groove, and in which the method of effecting an adjustment by varying the path in which the free end of the key lever is compelled to move is carried into effect by mechanism differing somewhat in details of construction from that previously described. Referring to said Fig. 7, 61 and 62 represent key levers operated through the keys 63 and 64. The end of key lever 61 is forked as shown more clearly in Fig. 8, and carries at its end the roller 65; lever 62 being similarly forked at its end and carrying a roller 66. The roller 65 engages and slides within a cam groove 67 formed in a cam piece 68, roller 66 in a similar manner engaging and sliding within the cam groove 69 carried in a cam piece 70. Both said cam pieces are fixedly mounted as through pins 71 upon a shaft 72 which is adapted to rotate in journals 73 carried by the frame 74 of the typewriter in any approved manner. Said shaft also carries, preferably pinned thereon, the lever 75, which corresponds to the lever 4 of Fig. 1, and may be connected with the platen by means similar to that shown in Fig. 1. Said means and said platen, however, are not shown in said Fig. 7. The cam levers 61 and 62 are respectively supported on brackets 76 and 77 which are carried on the frame 74, and are secured thereto preferably by cap bolts 78 engaging the bases 76^a and 77^a of said brackets and having capacity for longitudinal movement with respect to the frame 100 105 110

by reason of slots 79 provided in the base or frame for that purpose. The said levers 61 and 62 are respectively supported on the sides of the brackets 76 and 77 by means of pins 80 and 81 passed through slots in 115 120 125 130

the key lever, of which slots only that formed in lever 62 is shown, as at 82. Said pins 80 and 81 support the key levers and position the keys 63 and 64 at the desired elevation on the key board. For controlling the longitudinal position of the key lever 62 a link 83 is provided, said link being pivoted at one end through a pin 84 with said key lever 62. At its other end the link 83 is pivoted, as by bolt 85, with a sliding stud 86 carried on said bracket 77 with a capacity for being secured therein in various positions. The preferred construction of said sliding stud and the manner of adjusting the position of the same upon the bracket 77 are more clearly shown in Fig. 8, in which said stud 86 is shown in section on the plane $y-y$ in Fig. 7. Said bracket 77 is curved at its upper part and is provided with a slot 87, shown more clearly in Fig. 10. The faces of said slotted portion of the bracket are preferably beveled as shown in section in Fig. 8. Against one of such faces is located the front portion 86^a of the stud 86 and against the back face is located the back portion 86^b of the stud, the bearing surfaces of each such portions being preferably fitted to the beveled faces of the bracket adjacent the slot. By a screw 86^c the front and the back portions of the stud may be drawn together, clamping the stud 86 as a whole upon the beveled faces of the slotted portion of the bracket 77 in the desired position. Said slotted portion of the bracket 77 is finished so that its faces coincide with an arc circumscribed about the pivot 84 at a center. Thus the movement of the stud 86 upon the bracket 77 will not cause any longitudinal movement of the lever 62 which will disturb the position of the roller 66 carried upon the free end of said key lever. In a similar manner a stud 88 is slidably mounted upon a curved and slotted portion of the bracket 76, and is connected, as by a link 89, pivoted to the stud 88 at 90 and to the key lever 61 at 91, is adapted to control the longitudinal position of the said lever 61. The faces of that slotted portion of said bracket 76 on which said stud 88 is adapted to slide is in the form of an arc described about 91 as the center so that a change of position of said stud will not disturb position of the roller 65. From the method of supporting the key levers hereinbefore described it will be understood that the pins 80 and 81 will locate the keys 63 and 64 always at the desired elevation in the key board, and further that as said keys are depressed, the free ends of the key levers and the rollers carried thereon will swing about centers of which the exact locations are dependent upon the relative positions of the pins 80 or 81 with respect to the stud pivots 90 or 85; said centers however being more particularly determined, as heretofore men-

tioned in connection with Fig. 1 by the position of the stud pivots 85 and 90. Thus as the key 63 is depressed the roller 65 at the end of the lever 61 will swing upwardly in a path which is substantially that of an arc described about the stud pivot 90 as a center. In such movement it will traverse the cam groove 67 in the cam piece 68, such groove being designed in a manner similar to that hereinbefore described in connection with the groove 17 of Fig. 1, so that when the roller 65 reaches its upward limit of travel of movement in the cam groove 67 will have caused the cam piece 68 to rotate in an anti-clockwise direction by an amount adapted to cause the lever 75 connected with said cam piece through the shaft 73 to move downwardly sufficient to cause a lowering of the platen to the required position. In a similar manner the depression of the key 64 will cause the roller 66 to swing upwardly in a path which is principally controlled by the position of the pivot 85, in which upward movement it is adapted to slide in the groove 69 of the cam piece 70 and to rotate said cam piece 70 in a clockwise direction by an amount sufficient to cause the upward movement of the lever 75, and the elevation of the platen to the desired position. At the bottom of each of said grooves 67 and 69 are provided the lateral extensions 67^a and 69^a which permit the rotation of the cam piece in the cam groove of which the roller carried by the idle key lever is located, with respect to such roller, when the other key lever is actuated. It will further be seen that as the studs 88 and 86 are moved toward the upper end of the slotted portions of the brackets on which they are carried the effect will be to raise the points about which the rollers 65 and 66 swing, thus inclining the paths in which said rollers travel toward the left with respect to the normal paths followed by said rollers when the said studs are located near the center of said slotted portions. In a similar manner the lowering of said studs will cause paths to incline toward the right as compared with said normal paths. Thus the change of location of the pivots 85 and 90 through the positioning of the studs 86 and 88 affords a means for adjustment in the position to which the platen is raised or lowered in a manner analogous to that as hereinbefore described in connection with Fig. 1.

In Figs. 11, 12 and 13, is shown another embodiment of my invention of which the general construction is similar to that shown in Figs. 7, 8, 9 and 10, with the difference however, that there is a mechanical inversion with relation to the cam-grooves and the cam-rollers engaging the same; the cam-grooves being in Figs. 11, 12 and 13, being carried upon the ends of the key levers and being adapted to slidably engage

with the rollers by which the platen shifting lever is actuated. Referring to said Figs. 11, 12 and 13, 92 and 93 represent key levers operated through keys 94 and 95, which are supported respectively on the brackets 96 and 96^a in a manner preferably as shown and described in connection with Fig. 7. The platen shifting mechanism may be connected with the platen by means of mechanism preferably similar in construction with that shown in Fig. 1, and receiving its shifting movement from the lever 97 which corresponds to lever 4, of Fig. 1. The said platen and means connecting the same with said lever 97 are omitted in Fig. 11, as an operative arrangement of the same is fully shown in Fig. 1. Said lever 97 comprises a horizontal arm forming preferably an integral part of a bell crank lever, pivoted upon shaft 98 rotatably supported in the journals 99, and having a vertical extension 97^a, carrying at its upper portion a cylindrical member 97^b projecting on either side from said vertical arm 97^a as shown. At the end of said cylindrical member 97^b is carried rollers 100 and 101, preferably rotatably mounted thereon as by screws or studs 102 and 103. Preferably the head of each screw is somewhat larger than the diameter of the roller mounted thereon. Furthermore washers 104 and 105 are located between the cam roller and the end of the roller carrying support 97^b. For the sake of clearness however, the said washer 105 and the head of the screw 102 are omitted in the elevation shown in Fig. 11. At the free end of key lever 92 is provided preferably as an integral part of the same, as shown, the cam piece 106, in which cam piece is formed a cam groove 107 within which the roller 100 is adapted to slide. In a similar manner the free end of key lever 93 is provided with the cam piece 108 having the cam groove 109 formed therein, and slidably engaging the roller 101. The cam groove 107 is so formed that as the key 94 is depressed, tilting the key lever 92 and carrying its free end with the cam piece 106 located thereon upwardly, such upward movement of the cam groove 107, with respect to roller 100 will cause said roller to move toward the right, as shown in Fig. 1, and so produce a clockwise rotation of the vertical arm 97^a and of the horizontal lever 97, in consequence of which the platen will be elevated. In a similar manner the depression of the key 95 will cause an upward movement of the cam groove 109 carried in the cam piece 108 at the free end 60 of said key lever 93, which will cause a leftward motion of the roller 101 and an anti-clockwise rotation of the arm 97^a and the lever 97, resulting in a lowering of the platen. As hereinbefore explained in the 65 embodiment of my invention, the cam

groove 107 is provided with a lateral elongation 107^a situated at its upper end which permits the roller 100 to move leftward with respect to said cam piece 106 as the lever arm 97^a, carrying the said roller, is rotated in anti-clockwise direction in consequence of the upward movement of the cam piece 108. In a similar manner the groove 109 is provided with a lateral elongation 109^a at its upper end which will permit the movement toward the right of the roller 101 with respect to cam piece 108 when the key 92 is actuated and key 93 is in its normal position, both such lateral extensions being wider than the roller for the reasons explained in a previous portion of this specification. The washers 104 and 105, in co-operation with the heads of the screws 102 and 103, prevent the cam pieces from lateral displacement with respect to the rollers sliding within the cam grooves formed in such cam pieces. The key lever 93 is supported upon the bracket 96^a through the screw 110 fitting slidably within a laterally elongated slot 111. A similar construction is adopted in supporting key lever 92 upon the bracket 96. The key lever 92 is secured against lateral displacement by a link 112 pivoted at one end to the key lever 92 at 113, and engaging at its other end through a bolt 114 with a stud 115 slidable up and down upon the bracket 96 and adapted to be clamped in the desired position thereon through the screw 116, all being constructed and arranged as hereinbefore described in connection with Figs. 7, 8, 9, and 10. By loosening the screw 116 the height at which said stud 115 may be secured upon the bracket 96 may be varied, such a change in position operating 105 to change the location of the center about which said lever swings, in manner hereinbefore explained in connection with Figs. 7, 8, 9, and 10. Thus a means is provided by which the range of movement of the 110 rollers carried upon the arm 97^a and through which the lever 97 is caused to swing, may be more or less varied, thus providing a means for the adjustment of the position to which the platen is shifted. Padded stops 117 and 118 are provided to limit the swing of lever 92 and to stop such swing before impact of the roller 100 against the ends of the slot 107 can occur. Appropriate means, as for example the spring 119, is 115 provided to normally retain the lever 92 at its lower limit of rotation, at the same time permitting the same to swing upwardly when desired. Similar means not shown in Fig. 11 is employed to define the 120 limits of movement of the lever 93 and to yieldingly retain the same in its normally lowered position.

Figs. 14 and 15 show a modification in the manner of supporting the rollers en- 130

gaged by the cam pieces 106 and 108, which modification is more especially adapted to typewriting machines in which the platen elevating mechanism is operated through a 5 shaft which extends transversely across the machine, instead of upon a short shaft as shown at 98 in Fig. 13. In such case it may become necessary to provide an offset in the shaft in order to prevent interference between 10 said shaft and the cam pieces. Thus in Fig. 14, shaft 120 may be carried in bearings 121 and 122 suitably mounted on the frame of the machine in usual manner, on said shaft being secured a lever 123, corresponding in function to the lever 97 of Fig. 11, for actuating the platen. On said shaft are fixedly mounted two vertical arms 124 and 125, on the ends of which is carried a bar 126 lying substantially in alinement 15 with the shaft 120. On such bar are rotatably mounted rollers 127 and 128, which rollers may be retained on said bar 126 without lateral displacement by any approved means. On either side of each of said rollers 20 are preferably provided washers 129. Said rollers 127 and 128 fit and slide within cam grooves provided in the cam pieces 106 and 108, which may be assumed to be similar to those shown in Fig. 11. To avoid 25 interference with the shaft 120 by the lower ends of said cam pieces when the same are in their normal lowered positions as shown in Fig. 14, the shaft 120 is offset at 120^a by an amount sufficient to afford the necessary 30 clearance. In other respects the mechanism and mode of operation is similar to that shown in Figs. 11, 12 and 13.

Having described my invention I claim:—

1. In a typewriter, a vertically movable carriage carrying a platen normally located in a mid position, a movable lever arm, means connecting the said arm with said carriage for shifting the same to a higher or lower position in response to a predetermined movement of said lever arm, a pair of cam pieces having cam grooves formed therein, a pair of key levers carrying rollers and engaging said cam grooves, said rollers being each normally positioned adjacent one end of the cam groove engaged thereby and being adapted to swing in a fixed path about a central point as its key lever is operated and to traverse said groove, each of said cam grooves being so formed in its cam piece with relation to the path of the roller engaging the same that the traverse of one roller in its cam groove will cause the cam piece carrying the same to rotate in one direction and the traverse of the other roller in its groove will cause the cam piece carrying said groove to rotate in the other direction, connections whereby the rotative movement of the cam pieces is transmitted to said lever arm, and means for independently changing the paths of said rollers.
2. In a typewriter, a vertically movable carriage carrying a platen normally located in a mid position, a movable lever arm, means connecting the said arm with said carriage for shifting the same to a higher or lower position in response to a predetermined movement of said lever arm, a pair of cam pieces having cam grooves formed therein, a pair of key levers carrying rollers and engaging said cam grooves, said rollers being each normally positioned adjacent one end of the cam groove engaged thereby and being adapted to swing in a fixed path about a central point as its key lever is operated and to traverse said groove, each of said cam grooves being so formed in its cam piece with relation to the path of the roller engaging the same that the traverse of one roller in its cam groove will cause the cam piece carrying the same to rotate in one direction and the traverse of the other roller in its groove will cause the cam piece carrying said groove to rotate in the other direction, connections whereby the rotative movement of the cam pieces is transmitted to said lever arm, and means for independently changing the point about which each roller swings.
3. In a typewriter, a vertically movable carriage carrying a platen normally located in a mid position, a movable lever arm, means connecting the said arm with said carriage for shifting the same to a higher or lower position in response to a predetermined movement of said lever arm, a pair of cam pieces having cam grooves formed therein, a pair of key levers carrying rollers and engaging said cam grooves, said rollers being each initially positioned adjacent one end of the cam groove engaged thereby and being adapted to swing in a fixed path about a central point as its key lever is operated and to traverse said groove, each of said cam grooves being so formed in its cam piece with relation to the path of the roller engaging the same that the traverse of one roller in its cam groove will cause the cam piece carrying the same to rotate in one direction and the traverse of the other roller in its groove will cause the cam piece carrying said groove to rotate in the other direction, each cam piece being cut away adjacent the normal position of the roller lying therein to permit the movement of one cam piece with respect to the roller engaging its cam groove when the lever carrying the other member is operated, connections whereby the rotative movement of the cam pieces is transmitted to said lever arm, and means for independently changing the direction of the paths in which said rollers swing.
4. In a typewriter, a vertically movable carriage carrying a platen normally located in a mid position, a movable lever arm, means connecting the said arm with said

- carriage for shifting the same to a higher or lower position in response to a predetermined movement of said lever arm, a pair of cam pieces having cam grooves formed 5 therein, a pair of key levers carrying rollers and engaging said cam grooves, said rollers being each normally positioned adjacent one end of the cam groove engaged thereby and being adapted to swing in a fixed path about 10 a central point as its key lever is operated and to traverse said groove, each of said cam grooves being so formed in its cam piece with relation to the path of the roller engaging the same that the traverse of one 15 roller in its cam groove will cause the cam piece carrying the same to rotate in one direction and the traverse of the other roller in its groove will cause the cam piece carrying said groove to rotate in the other direction 20, each cam piece being cut away adjacent the normal position of the roller lying therein to permit the movement of one cam piece with respect to the roller engaging its cam groove when the lever carrying the 25 other member is operated, connections whereby the rotative movement of the cam piece is transmitted to said lever arm, and means for independently changing the point about which each roller swings.
- 30 5. The combination with a key lever having a key and carrying a cam engaging member adapted to swing in an upwardly inclining path, of coöperating supports for said lever; one support being vertically fixed and controlling the height of the lever key and the other support having capacity for vertical adjustment in position and controlling the inclination of said path through change in its vertical position.
- 35 6. The combination with a key lever having a key and carrying a cam engaging member adapted to swing in an upwardly extending path, of coöperating supports for said lever, comprising a vertically fixed support carrying said lever at a fixed height and having capacity for lateral play with respect thereto, and a vertically adjustable support controlling the lateral position of said lever and having a capacity for vertical play with respect thereto and determining by its position of adjustment the point about which the cam engaging member swings.
- 40 7. The combination with a key lever having a key and carrying a cam engaging member adapted to swing in an upwardly extending path, of coöperating supports for said lever, comprising a vertically fixed support carrying said lever at a fixed height and having capacity for lateral play with respect thereto, and a vertically adjustable support controlling the lateral position of said lever and having a capacity for vertical play with respect thereto and determining by its position of adjustment the point about which the cam engaging member

55 swings, said adjustable support being movable in an arc described about a fixed point on said lever as a center.

8. The combination with a key lever having a key and carrying a cam engaging roller, of supporting means for said lever comprising a bracket, a supporting screw or stud fixed on said bracket and engaging said key lever with a capacity for lateral movement with respect thereto, a stud 70 slideable upon said bracket and securable therein in various positions of vertical adjustment, and link pivotally attached at one end to said stud and at the other end to said lever, said stud being movable upon said bracket in an arc centered at the point of attachment of said link with said lever.

9. In a typewriting machine, or the like, the combination, with a movable platen normally located in an initial position, mechanism for shifting said platen to another position, such mechanism including a member carrying a cam surface and a coöperating member engaging said cam surface and adapted to slide therein, one of said members being arranged to swing in a prescribed path and being adapted in the course of such swing to effect a shift of the other or shiftable member into a predetermined location; of means for changing the direction of the path taken by said swinging member after leaving its normal position to vary the shifted position of the shiftable member.

10. In a typewriting machine, or the like, the combination, with a movable platen normally located in an initial position, mechanism for shifting said platen to another position, such mechanism including a member carrying a cam surface and a coöperating member engaging said cam surface and adapted to slide therein, one of said members being arranged to swing in a prescribed path and being adapted in the course of such swing to effect a shift of the other or shiftable member into a predetermined location, and means for communicating the movement of said shiftable member to the platen; of means for displacing the path of the movement of said swinging member to vary the shifted position of the shiftable member.

11. In a typewriting machine, or the like, the combination, with a movable platen normally located in an initial position, mechanism for shifting said platen to another position, such mechanism including a member carrying a cam surface and a coöperating member engaging said cam surface and adapted to slide therein, one of said members being arranged to swing about a central point and being adapted in the course of such swing to effect a shift of the other or shiftable member into a predetermined location, and means for communicating the

movement of said shiftable member to the platen; of means for changing the location of the point about which said swinging member turns to vary the shifted position 5 of the shiftable member.

12. In a typewriter, a movable platen normally located in an initial position, a cam piece having a cam groove formed therein, a key-lever having a portion engaging said 10 cam groove, said portion being adapted to swing in a prescribed path as said key-lever is operated and in such swing to traverse said cam groove, said groove being so formed in the cam piece with relation to 15 the swinging portion of the key-lever engaging the same that the traverse of said portion in the cam groove will cause the cam piece to rotate, connections whereby the rotative movement of said cam piece communicates a 20 shifting movement to the platen, and means for changing the location of the point about which the said key-lever swings to vary the amount of the rotative movement of said cam piece.

25 13. In a typewriter, a movable platen nor-

mally located in an initial position, a cam piece having a cam groove formed therein, and a key-lever having a portion engaging said cam groove, said portion being adapted to swing about a central point as said key-lever is operated and in the course of such swing to traverse said cam-groove, said groove being so formed in the cam piece with relation to the movement of the swinging portion of the key-lever engaging the 30 same that the traverse of said portion in the cam groove will cause the cam piece to rotate, connections whereby the rotative movement of said cam piece communicates a shifting movement to the platen, and means 35 for changing the location of the point about which the said key-lever swings to vary the amount of the rotative movement of said cam piece.

In testimony whereof I affix my signature 40 in presence of two witnesses.

ARTHUR W. WEEDEN.
